UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed March 12, 1925, Serial No. 15,057. Renewed November 10, 1930.

This invention relates to hoisting mechanisms, and more especially to the portable type of hoist.

Portable hoisting mechanisms, particularly those of the double drum type, are extensively used for what is called "slushing", in the operation of which a scraper will be dragged back and forth through the material to be loaded. It happens sometimes that the load is too great for normal starting; and should the hoist be of the type wherein the drums are driven while the motor is coming up to speed, the motor, if of the electric type, is very liable to be burnt out. In hoisting mechanisms, such as herein disclosed, a reversible type of motor is used with suitable means to drive automatically one drum or the other in accordance with the direction of motor rotation and thus cause the drums to be reversely rotatable. An object of the invention is accordingly to provide improved means whereby the driving torque can be gradually applied to the motor while retaining the feature of automatic alternate clutching of the drums. A further object is to provide improved means for supporting the drums. A still further object is to provide improved means for driving the drums from a reversible type of motor and improved means for supporting the motor in a suitable standard. In the accompanying drawings I have shown for purposes of illustration one form which my invention may assume in practice.

In these drawings,—

Fig. 1 is a longitudinal section showing the driving motor in elevation.

Fig. 2 is a fragmentary detail view of the automatic clutching mechanism taken in section on line 2—2 of Fig. 1.

In the illustrative embodiment of my invention a base 1 supports at opposite ends a removable standard 2 and a fixed standard 3 having stepped bores 4 and 5 to receive, herein, an electric motor casing 6 having corresponding enlarged and reduced portions. A motor head 7 clamps by bolts 8 a split ring 9 against the end of the standard 3, thereby to longitudinally clamp upon engagement of shoulders 4', 6' the motor cas-

ing 6 against movement in the standard. It is also clear that instead of using the ring 9, the flange of the head 7 could be radially extended to overlie the outer end of the standard 3 to take the place of ring 9. To assemble such a construction would necessitate removing the head 7 before insertion of the main body of the casing 6 through the right hand end of the bores 4 and 5, after which replacement of the head 7 would cause the necessary clamping effect; whereas with the other construction, the head would only have to be loosened to permit slipping in of the split ring 9 between the adjacent ends of the head and casing. A drum or driver member 10 is rotatably mounted on the casing by a bearing 11 at one end; and is supported at its other end by a plate 12 having a stub shaft 13 journaled as by bearings 14 in a hub 15, in turn journaled in the standard 2. Formed integral with the hub 15 is a radial flange 16 carrying an internal reaction gear 17 adapted to be held against rotation by a manually operable friction band 18. Rotatably journaled upon the drum 10 are drums 19 and 20 having at their adjacent ends brake drums 21 and 22 engageable by usual friction bands 23, 24. The brake drums form a chamber 25 intermediate the adjacent ends of the drums 19 and 20 within which is disposed a longitudinally slid able ratchet ring 26 splined at 27 to, and surrounding, the drum 10. This ring has on its opposite sides reversely disposed ratchet teeth 28 and 29 respectively engageable with teeth 30 and 31 carried on the drums 19 and 20 respectively. The teeth carried by the respective members are provided with cam surfaces 30', 28', 29' and 31' in order to effect automatic shifting hereinafter described.

Driving gearing for 90
rotating the drum or driver member 10 comprises a motor pinion 32 fixed to the armature shaft of the electric motor and meshing with a gear 33 fixed to a shaft 34 journaled in a bracket 35. Fixedly carried at the opposite end of said shaft is a pinion 36 meshing with a gear 37 fixed to a shaft 38 journaled in bearings 39 carried by the plate 12. A pinion 40 is fixed to the shaft 38 at its opposite end, and this pinion meshes with a gear 95
100

41 journaled upon a stub shaft 42 projecting outwardly from the plate 12. The internal gear 17 and gear 41 continuously mesh. During driving of the drums any tendency for the motor casing 6 to rotate will be prevented by having keys 43 disposed between the casing and standard 3.

In operation, it is always highly desirable in the case of an electric motor to have the same come up to its normal speed before applying a load; for otherwise the current might be so excessive as to burn out the armature windings. Thus, assuming that the motor has come up to speed alone, and is rotating in a predetermined direction, the friction band 18 will be applied to gradually cause the gearing 17 and 32 to 41 to rotate the drum 10, whereupon the ratchet 26 will automatically shift into engagement with the drum which is driven during the particular direction of rotation of the motor. When it is desired to drive the other drum, the friction band 18 will be released and the motor reversed and brought up to speed, after which reapplication of the band 18 will cause rotation of the drum 10 in the opposite direction; and accordingly the ratchet ring 26 will shift into engagement with the other drum. If it is found that the load is too great when the ratchet ring engages the teeth 30 or 31, the operator can, immediately after the ring is shifted, release the band 18 and gradually reapply the same to thereby prevent stalling of the motor resulting in the possibility of burning out the motor.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A hoisting mechanism comprising a pair of winding drums, a reversible motor, and operative driving connections between said motor and said drums including means for connecting one drum to said motor and for disconnecting the other drum therefrom automatically in accordance with the direction of motor rotation, said driving connections including a frictionally controlled reaction gear.

2. A hoisting mechanism comprising a driver member, a pair of winding drums, a reversible motor, operative driving connections between said motor and said driver member including a frictionally controlled reaction gear, and means operative when said driver member is driven by said motor for connecting one drum to said driver member and for disconnecting the other drum there-

from automatically in accordance with the direction of motor rotation.

3. A hoisting mechanism comprising a driver member, a pair of winding drums, a reversible motor, operative driving connections between said motor and said driver member including a frictionally controlled reaction gear and means operative when said reaction gear is frictionally controlled to cause the driver member to be driven and including a shiftable member connected to said driver member adapted to alternatively engage said drums for connecting one drum to said driver member and for disconnecting the other drum therefrom automatically in accordance with the direction of motor rotation.

4. A hoisting mechanism comprising a pair of winding drums each having ratchet teeth carried thereby, a reversible motor, and operative driving connections between said motor and said drums including controlling means operable at will for frictionally connecting said drums and said motor or releasing the same therefrom to permit running of said motor while said drums remain stationary, said driving connections including a shiftable ratchet ring alternatively engageable with the ratchet teeth on said drums automatically in accordance with the direction of motor rotation.

5. A hoisting mechanism comprising a pair of winding drums, each having ratchet teeth carried thereby, a reversible motor, and operative driving connections between said motor and said drums including controlling means operable at will for frictionally connecting said drums and said motor or releasing the same therefrom to permit running of said motor while said drums remain stationary, said driving connections including a ratchet ring, and means formed on said ratchet ring for effecting shifting of the latter to alternatively connect said drums to said motor automatically in accordance with the direction of motor rotation.

6. A hoisting mechanism comprising a pair of winding drums, a reversible motor, and operative driving connections between said motor and said drums including a frictionally controlled reaction gear, said driving connections including means disposed between adjacent ends of said drums and operable to alternatively connect said drums to said motor automatically in accordance with the direction of motor rotation.

7. A hoisting mechanism comprising a rotatable casing, a pair of winding drums journaled on said casing, a reversible motor, operative driving connections between said motor and said casing including controlling means operable at will for frictionally connecting said casing and said motor or releasing the same therefrom to permit running of said motor while said casing remains sta-

tionary, and means operable when said motor is connected to said casing by said controlling means for connecting one drum to said casing and for disconnecting the other drum therefrom automatically in accordance with the direction of motor rotation.

8. A hoisting mechanism comprising a rotatable casing, a pair of winding drums rotatable about said casing, a reversible motor, operative driving connections between said motor and said casing including a driver gear carried by said casing and a frictionally controlled reaction gear with which said driver gear is constantly meshed, and means operable when said reaction gear is frictionally controlled to produce rotation of said casing for connecting one drum to said casing and for disconnecting the other drum therefrom automatically in accordance with the direction of motor rotation.

9. A hoisting mechanism comprising a rotatable casing, a pair of winding drums rotatable about said casing, a reversible motor, operative driving connections between said motor and said casing including a driver gear carried by said casing and a frictionally controlled reaction gear with which said latter gear is constantly meshed, and means operable when said reaction gear is frictionally controlled to produce rotation of said casing for connecting one drum to said casing and for disconnecting the other drum therefrom automatically in accordance with the direction of motor rotation, said automatic means including a shiftable element connected to said casing and alternatively engageable with said drums.

10. A hoisting mechanism comprising a rotatable casing, a pair of winding drums rotatable about said casing, a reversible motor having a stationary casing on which said rotatable casing is journaled, operative driving connections between said motor and said rotatable casing including controlling means operable at will for frictionally connecting said casing to said motor or releasing the same therefrom to permit running of said motor while said rotatable casing remains stationary, and means operable when said motor and rotatable casing are connected by said controlling means for connecting one drum to said rotatable casing and for disconnecting the other drum therefrom automatically in accordance with the direction of motor rotation.

11. A hoisting mechanism comprising a rotatable casing, a pair of coaxial winding drums journaled thereon, a reversible motor having a stationary casing on which said rotatable casing is journaled, operative driving connections between said motor and said rotatable casing including a driver gear carried by said casing and a frictionally controlled reaction gear with which said driver gear is constantly meshed, and means operable when

said reaction gear is frictionally controlled to produce rotation of said casing and including a shiftable element disposed between the adjacent ends of said drums and connected to said rotatable casing for connecting one drum to the latter and for disconnecting the other drum therefrom automatically in accordance with the direction of motor rotation.

12. A hoisting mechanism comprising a reversible motor having a stationary casing, a rotatable casing journaled on said stationary motor casing, a pair of relatively rotatable winding drums, operative driving connections between said motor and said rotatable casing, and means for alternatively connecting said drums to said rotatable casing automatically in accordance with the direction of motor rotation.

13. A hoisting mechanism comprising a motor having a stationary casing, a rotatable casing journaled on said stationary motor casing, a pair of relatively rotatable winding drums, operative driving connections between said motor and said rotatable casing, and means for connecting said drums to said rotatable casing.

14. A hoisting mechanism comprising a frame, a motor having a stationary motor casing secured to said frame, a rotatable casing journaled at one end on said stationary motor casing and at the other end on said frame, a pair of relatively rotatable winding drums journaled on said rotatable casing, operative driving connections between said motor and said rotatable casing, and means for alternatively connecting said drums to said rotatable casing.

15. A hoisting mechanism comprising a frame, a motor having a stationary casing secured to said frame, a rotatable casing journaled at one end on said stationary motor casing and at the other end thereof on said frame, a pair of relatively rotatable winding drums journaled on said rotatable casing, operative driving connections between said motor and said rotatable casing, and means including a shiftable member disposed between the adjacent ends of said drums for alternatively connecting the latter to said rotatable casing.

16. A hoisting mechanism comprising a motor having a stationary casing, a rotatable casing journaled on said stationary motor casing, a pair of relatively rotatable winding drums journaled on said rotatable casing, operative driving connections between said motor and said rotatable casing including controlling means operable at will for frictionally connecting said rotatable casing to said motor or for releasing the same therefrom to permit running of said motor while said rotatable casing remains stationary, and means for connecting said drums to said rotatable casing.

17. A hoisting mechanism comprising a

- motor having a stationary casing, a rotatable casing journaled on said stationary motor casing, a pair of relatively rotatable winding drums journaled on said rotatable casing, operative driving connections between said motor and said rotatable casing, and means for connecting said drums to said rotatable casing.
18. A hoisting mechanism comprising a motor having a power shaft and a stationary casing, a driver member, a plurality of relatively rotatable winding drums journaled on said driver member, said motor casing providing a support for said driver member so that one of the drums surrounds the motor casing, and operative driving connections between said power shaft and said winding drums including said driver member.
19. A hoisting mechanism comprising a reversible motor, a pair of winding drums, and operative driving connections between said motor and drums for alternatively driving said drums in opposite directions by said motor automatically in accordance with the direction of motor rotation, said driving connections including a single frictionally controlled reaction gear.
20. A hoisting mechanism comprising a pair of coaxial winding drums, a motor having a casing, and operative driving connections between said motor and drums including a member for supporting said drums, said member being rotatable relative to said motor casing on the axis of said drums, gearing driven by said motor carried by said supporting member, a frictionally controlled reaction gear meshing with a gear carried by said supporting member for controlling rotation of said supporting member, and means alternatively engageable with said drums to produce rotation of the engaged drum upon rotation of said supporting member.
21. A hoisting mechanism comprising a motor having a motor casing, a rotatable driving casing, operative driving connections between said motor and said driving casing for rotating the latter relative to said motor casing including gearing carried by said driving casing and a friction controlled reaction gear with which said gearing constantly meshes, a pair of relatively rotatable winding drums, and means for alternatively connecting said drums to said casing.
22. A hoisting mechanism comprising a motor having a motor casing, a rotatable supporting casing, a pair of relatively rotatable winding drums rotatably mounted thereon, said supporting casing being rotatable relative to said motor casing, and operative driving connections between said motor and said winding drums including said supporting casing and means splined thereto, said splined means being connectible with said winding drums to produce rotation thereof in opposite directions only.
23. A hoisting mechanism comprising a frame having spaced supporting standards, a reversible motor having a stationary casing carried by one of said standards, a rotatable casing journaled at one end thereof on said stationary motor casing and at the other end thereof on said other standard, a pair of winding drums rotatably supported on said rotatable casing, operative driving connections between said motor and said rotatable casing including gearing carried by the latter and revolving therewith and a frictionally controlled reaction gear with which said gearing constantly meshes, said reaction gear being rotatably supported by said other standard and when released being free to rotate to permit running of said motor while said drums remain stationary, and means for connecting one drum to said rotatable casing and for disconnecting the other drum therefrom automatically in accordance with the direction of motor rotation, said automatic means including a ratchet element automatically shiftable upon reverse rotation of said motor.
24. A hoisting mechanism comprising a pair of coaxial relatively rotatable winding drums, a motor having a stationary casing acting as a support for said drums, and operative driving connections between said motor and each of said drums including manually operable friction controlling means, said controlling means permitting running of said motor while said drums remain stationary, both of said drums being disposed at one end of said motor with one of said drums surrounding said motor casing.
25. A hoisting mechanism comprising a pair of coaxial relatively rotatable winding drums, a motor having a stationary casing acting as a support for said drums, and operative driving connections between said motor and each of said drums whereby the latter may be alternatively driven including manually operable friction controlling means, said controlling means permitting running of said motor while said drums remain stationary, both of said drums being disposed at one end of said motor with one of said drums surrounding said motor casing.
26. A hoisting mechanism comprising a motor having a stationary casing providing a cylindrical bearing surface on its periphery, a supporting standard having a bore with a shoulder formed therein, said motor casing being receivable in said bore and having a shoulder engaging the shoulder of the bore, a winding mechanism having at one end an internal bearing surface surrounding and journaled on said bearing surface on the periphery of said casing, means separate from said casing for supporting the other end of said winding mechanism, operative driving connections between said motor and said winding mechanism, clamp

ing means having a projecting portion for engaging said supporting standard, and means for securing said clamping means to said motor casing.

27. A hoisting mechanism comprising a motor having a stationary casing providing a cylindrical bearing surface on its periphery, a supporting standard having a bore, said motor casing being receivable in said bore and having a shoulder engaging said standard, a winding mechanism having at one end an internal bearing surface surrounding and journaled on said bearing surface on the periphery of said casing, means separate from said casing for supporting the other end of said winding mechanism, operative driving connections between said motor and said winding mechanism, said motor casing including a plurality of cooperating elements adapted to be clamped together, and an insert which when clamped between said cooperating elements is adapted to engage said standard for securing said motor casing within said bore.

28. A hoisting mechanism comprising a pair of winding drums, a driving shaft rotatable in opposite directions by power, operative driving connections between said shaft and said drums including means for connecting one drum to said motor and for disconnecting the other drum therefrom, or vice versa, automatically in accordance with the direction of shaft rotation, said driving connections including a frictionally controlled reaction gear.

29. A hoisting mechanism comprising a driver member, a pair of winding drums, a reversibly rotatable driving shaft, operative driving connections between said shaft and said driver member including a frictionally controlled reaction gear, and means operative when said reaction gear is frictionally controlled to cause the driver member to be driven and including a shiftable member connected to said driver member and adapted to engage said drums alternatively, for connecting one drum to said driving member and for disconnecting the other drum therefrom, or vice versa, automatically in accordance with the direction of motor rotation.

30. A hoisting mechanism comprising a pair of winding drums each having ratchet teeth carried thereby, a reversibly rotatable driver shaft, and operative driving connections between said shaft and said drums including controlling means operable at will for frictionally connecting said drums and said shaft or releasing the former from the latter to permit said drums to be stationary though said shaft is rotated, said driving connections including a ratchet ring and means formed on said ratchet ring for effecting shifting of the latter to connect said drums alternatively in driven relation with

said shaft automatically in accordance with the direction in which said shaft is rotated.

31. A hoisting mechanism comprising a pair of winding drums, a reversibly rotatable driving shaft, and operative driving connections between said shaft and said drums including a frictionally controlled reaction gear, said driving connections including means disposed between adjacent ends of said drums and operative to connect said drums alternatively to said shaft automatically in accordance with the direction of shaft rotation.

32. A hoisting mechanism comprising a rotatable casing, a pair of winding drums journaled on said casing, a reversibly rotatable driving shaft, operative driving connections between said shaft and said casing including controlling means operable at will for frictionally connecting said casing in driving relation with said shaft or interrupting said driving connection to permit said casing to remain stationary though said shaft be rotated, and means operable when said shaft is connected in driving relation with said casing by said controlling means for connecting one drum to said casing and for disconnecting the other drum therefrom automatically in accordance with the direction of shaft rotation.

33. In a hoisting mechanism, a rotatable casing, a pair of winding drums rotatable about said casing, a reversibly rotatable driving shaft, operative connections between said shaft and casing including a driving gear carried by said casing, and a frictionally controlled reaction gear with which said driver gear constantly meshes, and means operable when said reaction gear is frictionally controlled to produce rotation of said casing for connecting one drum to said casing and for disconnecting the other drum therefrom automatically in accordance with the direction of rotation of said driving shaft.

34. In a hoisting mechanism, a rotatable casing, a pair of winding drums rotatable about said casing, a reversibly rotatable driving shaft, operative connections between said shaft and casing including a driving gear carried by said casing, and a frictionally controlled reaction gear with which said driver gear constantly meshes, and means operable when said reaction gear is frictionally controlled to produce rotation of said casing for connecting one drum to said casing and for disconnecting the other drum therefrom automatically in accordance with the direction of rotation of said driving shaft, said automatic means including a shiftable element connected to said casing and alternatively engagable with said drums.

In testimony whereof I affix my signature.
CHARLES F. OSGOOD.

CERTIFICATE OF CORRECTION.

Patent No. 1,792,467.

Granted February 10, 1931, to

CHARLES F. OSGOOD.

It is hereby certified that error appears in the printed specification of the above numbered patent requiring correction as follows: Page 2, line 73, claim 3, after the word "gear" insert a comma; page 5, line 50, claim 29, for the word "motor" read shaft; and that the said Letters Patent should be read with these corrections therein that the same may conform to the record of the case in the Patent Office.

Signed and sealed this 6th day of October, A. D. 1931.

M. J. Moore,
Acting Commissioner of Patents.
